(57) **CLAIM**

The ornamental design for a bracket for a shower bar, as shown and described.

DESCRIPTION

FIG. 1 is a perspective view of the front of a bracket for a shower bar;

FIG. 2 is an elevation view of the front thereof;

FIG. 3 is an elevation view of the rear thereof;

FIG. 4 is an elevation view of a side thereof;

FIG. 5 is a plan view of the top thereof;

FIG. 6 is plan view of the bottom thereof; and,

FIG. 7 is a perspective view thereof showing a complete shower bar (portions not claimed shown with broken lines). The broken line showing the shower bar and anchors coupled in FIG. 7 is for illustrative purposes only and forms no part of the claimed design.
